(57) **CLAIM**

The ornamental design for a medication holding device, as shown and described.

DESCRIPTION

FIG. 1 shows a perspective view of a medication holding device;

FIG. 2 shows a front view of the medication holding device; FIG. 3 shows a rear view of the medication holding device; FIG. 4 shows a right side view of the medication holding device;

FIG. 5 shows a left side view of the medication holding device;

FIG. 6 shows a top plan view of the medication holding device; and,

FIG. 7 shows a bottom plan view of the medication holding device.

The shade lines in the Figures show contour and not surface ornamentation.

1 Claim, 5 Drawing Sheets
